UNITED STATES PATENT OFFICE.

TONY ALEXANDER, OF BOGUE CHITTO, MISSISSIPPI.

LOCOMOTIVE ATTACHMENT.

SPECIFICATION forming part of Letters Patent No. 368,366, dated August 16, 1887.

Application filed January 13, 1887. Serial No. 224,260. (No model.)

To all whom it may concern:

Be it known that I, TONY ALEXANDER, of 5 Bogue Chitto, in the county of Lincoln and State of Mississippi, have invented a new and Improved Locomotive Attachment, of which the following is a specification, reference being had to the annexed drawings, forming a part thereof, in which—

Figure 1 is a plan view of my improved locomotive attachment. Fig. 2 is a side elevation. Fig. 3 is an elevation of the opposite side. Fig. 4 is an inverted plan view with portions removed; and Fig. 5 is a detailed plan view, partly in section, of the same.

Similar letters of reference indicate corresponding parts in all the views.

The object of my invention is to provide an attachment to locomotives to be used in place of the pilot, or attached to the ordinary pilot, 20 for removing obstructions from the track and throwing them to one side.

My invention consists in a spring-frame attached to the front of a locomotive and arranged to be bowed, and in the combination therewith of a spring-actuated catch for retaining it under strain, and a bar connected with the spring-actuated catch for releasing the spring-frame by contact with an obstruction on the railway-track.

My improvement is designed to be attached to a locomotive in lieu of the ordinary pilot or to be applied to the pilot, as circumstances may require. In the present case I shall describe my improvement as applied to a locomotive in 35 place of the pilot.

To the front of the locomotive is secured a frame, A, formed of the triangular part B, which is composed of the cross-bar *a*, the longitudinal bar *b*, and the two oblique bars *c c'*, 40 which are attached to the cross-bar and to the outer end of the longitudinal bar. To the cross-bar *a* of the triangular frame B are secured the uprights *d*, to the upper ends of which is fastened a cross-bar, *e*. The triangular frame B is braced by the oblique braces *f*, 45 extending from the forward end of the bar *b* to the bar *e*.

To the frame B, at the juncture of the cross-bar *a* with the oblique bar *c*, is secured a casting, C, and to the bar *e*, immediately above the casting C, is secured an angle-plate, D.

To the angle-plate D and casting C are se-

cured the ends of the springs E E', formed of flat bars of spring-steel or other suitable spring material, having their ends bent at right angles and secured by bolts to the casting C and angle-plate D. The springs are connected with each other by vertical bars *g*, which are clamped to the springs by bolts *h* and short bars *i*, the bolts passing through holes in the bars *g* above and below each spring and through holes in the short bar *i*. To the front or outer surface of each spring E E' is secured a rubber covering, *j*.

In the oblique bar *c*, and in an arm, *k*, attached to the bar *e*, is journaled a reel, F, to which are attached three chains, G G' G'', which are secured to eyes *l*, projecting from the bar *g*, attached to the free extremities of the springs E E'. Upon the shaft of the reel F is secured 70 a pinion, *m*, and upon the bar *e* is placed a steam or air cylinder, H, provided with a piston and piston-rod, *n*, connected by an arm, *o*, with a rack, *p*, guided in a groove in the side of the cylinder H and arranged to engage the pinion 75 *m*. The cylinder H receives steam or air under pressure from a pipe entering a hole, *q*, in the rear end of the cylinder. To the bar *e* is pivoted a right-angled pawl-lever, *r*, one end of which is capable of engaging the rack *p*, 80 while the other end is connected with a rod, *s*, which extends to the cab of the locomotive.

To the under surface of the frame A is pivoted a catch-lever, *t*, which is pressed by a spring, *u*, backward toward the rear of the 85 frame A. The inner end of the catch-lever *t* is prolonged beyond the pivot of the lever to the center of the frame B, and is connected with the bar *v*, which extends beyond the forward end of the frame and is provided with a 90 curved cross-arm, *w*, which is of sufficient length to reach from one track-rail to the other. The bar *v* is supported by a standard, *a'*, which extends upward through a slot in the bar *v*, and carries two rollers, *b'*, which rest upon the 95 top of the bar *b* and support the bar *v* and the cross-arm *w* a short distance above the track. The rollers *b'* are protected by a guard, *c'*. Upon the extremity of the bar *b* is secured a post, *d'*, which is supported by the braces *e'f'*, 100 extending backward and secured to the forward edge of the bar *e*. To the front side of the post *d'*, near the top thereof, is secured the draw-bar *g'*.

The springs E E' are placed in the position for use by winding the chain G upon the reel F and bringing the end bar, g, into engagement with the catch-lever t. The spring-frame 5 is thus held under strain by the catch-lever t until the cross-arm w, carried by the bar v, strikes an obstruction upon the track, when the catch-lever t is turned on its pivot, so as to release the spring-frame, allowing it by its own 10 elasticity to straighten, and in so doing to remove the obstruction to one side of the track out of the path of the locomotive. The spring-frame is replaced in the position of use by admitting steam or air under pressure to the 15 cylinder H, forcing out the rack p, which, by its engagement with the pinion m, turns the reel F and winds the chains G G' G² and brings the bar g into engagement with the catch-lever t.

20 Should the engineer at any time desire to prevent the operation of the device, he can do so by bringing the pawl-lever r into engagement with the teeth of the rack p by pushing the rod s. The rubber covering of the springs 25 E E' prevents injury to the apparatus while it is in operation.

Having thus fully described my invention, I claim as new and desire to secure by Letters Patent—

30 1. The combination, with a locomotive, of a spring-frame formed of the springs E E', the vertical bars g, and means, substantially as shown and described, for straining and releasing the spring-frame.

35 2. The combination, with the pilot of a locomotive, of a spring covering formed of the springs E E', vertical bars g, and the retaining catch-lever t, substantially as shown and described.

3. The combination of the frame A, the 40 springs E E', the vertical bars g, the spring-actuated catch-lever t, and the bar v, provided with the cross-arm w, substantially as shown and described.

4. The combination of the frame A, the 45 springs E E', the vertical bars g, the spring-actuated catch-lever t, the bar v, provided with the cross-arm w, the chains G G' G², the reel F, and means, substantially as shown and described, for operating the reel. 50

5. In a locomotive attachment, the combination of the frame A, the springs E E', secured to the frame, the vertical bars g, secured to the springs E E', the chains G G' G², the reel F, the pinion m, the rack p, the cylinder 55 H, containing the piston and piston-rod connected with the rack p, the spring-actuated catch-lever t, and the bar v, connected with the catch-lever and provided with the cross-arm w, substantially as shown and described. 60

6. In a locomotive attachment, the combination of the frame A, the springs E E', secured to the frame, the vertical bars g, secured to the springs E E', the chains G G' G², the reel F, the pinion m, the rack p, the cylinder 65 H, containing the piston and piston-rod connected with the rack p, the spring-actuated catch-lever t, the bar v, connected with the catch-lever and provided with the cross-arm w, and the pawl-lever r, arranged to engage 70 the rack p and the rod s, connected therewith, substantially as shown and described.

TONY ALEXANDER.
